CLAIM

The ornamental design for a cover plate for an air freshener, as shown and described.

DESCRIPTION

FIG. 1 is an isometric view of a front, bottom, and right side of an ornamental design for a cover plate for an air freshener; FIG. 2 is a front elevational view of the cover plate of FIG. 1; FIG. 3 is a front elevational view of a different embodiment of the cover plate of FIG. 1; FIG. 4 is a front elevational view of another embodiment of the cover plate of FIG. 1; FIG. 5 is a front elevational view of yet a different embodiment of the cover plate of FIG. 1; FIG. 6 is a front elevational view of still a different embodiment of the cover plate of FIG. 1; and, FIG. 7 is a front elevational view of still another embodiment of the cover plate of FIG. 1. The broken lines showing of the subject matter shown is for the purpose of depicting environmental structure and forms no part of the claimed design. The drawings are lined for color.
